UNITED STATES PATENT OFFICE

163,741

SCARF

Reneé Boetschi, Beverly Hills, Calif., assignor of one-half to Iris Flores Tillinghast, Hollywood, Calif.

Application July 2, 1949, Serial No. 3,686

Term of patent 3½ years

(Cl. D3—16)

To all whom it may concern:

Be it known that I, Reneé Boetschi, a citizen of the United States and residing at Beverly Hills, in the county of Los Angeles, State of California, have invented a new, original, and ornamental Design for a Scarf, of which the following is a specification, reference being had to the accompanying drawing, forming part thereof, in which:

Fig. 1 is a front perspective view of a scarf, showing my new design, and

Fig. 2 is a rear perspective view thereof.

I claim:

The ornamental design for a scarf, substantially as shown.

RENEÉ BOETSCHI.
